Inventor.

Fred H. Cutler

UNITED STATES PATENT OFFICE.

FRED H. CUTLER, OF BUFFALO, NEW YORK.

DESK ATTACHMENT.

SPECIFICATION forming part of Letters Patent No. 367,789, dated August 9, 1887.

Application filed March 16, 1887. Serial No. 231,195. (No model.)

To all whom it may concern:

Be it known that I, FRED H. CUTLER, a citizen of the United States, residing in the city of Buffalo, in the county of Erie and State 5 of New York, have invented a new and useful Improvement in Desk Attachments, of which the following is a specification.

My invention relates to office-desks, and is an attachment therefor designed as a receptacle for waste papers and other office refuse.

The object of my invention is twofold—first, to economize space in the office-room, and, second, to conceal from view unsightly office refuse.

15 I accomplish the objects of my invention in the manner illustrated in the accompanying drawings, in which—

Figure 1 is a sectional view of an office-desk provided with my improvement, and 20 illustrates the preferred location of the receptacle. Fig. 2 is a perspective view of the receptacle or pocket itself, illustrating the configuration preferred by me; and Fig. 3 is a similar view of one form of bracket employed 25 by me for securing the pocket in position.

Like letters of reference refer to corresponding parts in each figure of the drawings.

A and A represent the sides of the receptacle. These are of half-inch stuff ripped out 30 in the shape shown in Figs. 1 and 2.

B represents the back and bottom of the receptacle. This is one continuous sheet of some suitable flexible material, such as sheet metal, leather, press-board, or the like.

35 b is a tie-rod serving also as a supporting-rod in the manner shown in Fig. 1; and a and a represent that portion of the edge of the sides A and A designed to come in contact with the writing-bed of the desk, and serve 40 thereby as a sort of a shoulder or stop to prevent the contracting or closing of the mouth of the receptacle by the weight or gravity of its body, for one will readily observe that a slight change in the configuration of the sides 45 A and A at this point, or a change in the location of the supporting-rod, will correspondingly change the opening or mouth of the receptacle.

50 S and S represent the bracket, or that portion of the device designed for the support of the receptacle proper, O being the

base-piece, designed for attaching to the desk by means of screws or the like, and S and S being the hooks or supports, designed for the reception of the tie-rod b in the manner shown 55 in Fig. 1, where it is secured to the under side of the writing-bed X of the desk Y.

It will be readily understood that Fig. 1 represents but one half of a desk, and that the receptacle or pocket is there shown as directly above and in front of the knees of the person sitting at the desk, yet sufficiently removed therefrom to prevent contact therewith. This position not only conceals the device and its contents from view, but places it 60 in a convenient position for the reception of any and all desk refuse. It is in easy reach of the occupant of the desk, and may be hung upon the bracket or removed therefrom by him without rising from his chair.

To hang the basket on the hooks S and S, 65 tilt it, as indicated by dotted lines in Fig. 1, and it should be tilted in like manner for removal therefrom.

This device occupies no floor-spaces, as do 70 the ordinary waste-baskets. It is applicable to all desks or tables, and may be varied in size or style to correspond with the desk to which it is to be attached or to suit the caprice of its owner, and its location may be varied without 75 departing from the spirit of my invention.

What I claim, therefore, and desire to secure by Letters Patent, is—

1. The herein shown and described desk attachment, consisting of a tilting waste receptacle provided with a supporting-rod, b, and having sides A and A, each provided with a shoulder, a, and united and held in position by means of bottom B and supporting-rod b, substantially as shown, and for the purpose 85 set forth.

2. The herein shown and described desk attachment, consisting of a receptacle having sides A A, bound together by means of a bottom, B, and supported by a bracket consisting 90 of a bed-piece, O, provided at its ends with supporting-hooks S S, all substantially as 95 shown.

FRED H. CUTLER.
